UNITED STATES PATENT OFFICE.

MAXIMILIAN S. HACHITA, OF WILKES-BARRE, PENNSYLVANIA.

COAL JIG.

Application filed May 14, 1925. Serial No. 30,161.

This invention relates to apparatus employed in the cleaning of coal of the type generally known in the art as coal jigs.

The general object of the invention is to provide an improved and novel construction of coal jig by the employment of which coal may be more thoroughly and efficiently separated from impurities consisting of earthy matter, such as rock, stone, slate, pebbles, sand, pyrite, etc., than heretofore has been practical.

It is also an object of the invention to provide an improved and novel construction of coal jiggling apparatus whereby a mixture of 15 pure coal, coal of low grade or "middlings" as it is called, and earthy material, such as rock, stone, etc., may be separated into its three constituents or separate parts.

Other objects of the invention are,—to provide an apparatus of novel construction such that the thickness of the bed of material upon the jig or separating pan is maintained at a minimum, so that the pulsating water operating thereon may have a maximum effect in bringing about separation; to provide an apparatus of novel construction such that the bed of material upon the bottom of the jig or separating pan shall be allowed to expand freely, thereby producing a porous bed 25 such that the separate particles or elements thereof may be subjected to approximately equal forces produced by the pulsating action of the water; to provide a novel construction of jig pan comprising troughs extending longitudinally thereof, along which the heavier 30 portions of material are caused to travel or flow, with which troughs are associated means whereby the effect of the pulsations of water in one trough is independent of the effect 35 of the pulsations in other troughs; to provide means extending transversely of the said troughs for causing lateral movement transversely of the said troughs of the lighter portion of the material being treated, for instance, pure coal; to provide novel means 40 whereby the portion of the material which does not require jiggling or cleansing is discharged in the early part of the jiggling operation, so that the portion of the material 45 being treated which reaches the main jig area of the jig pan contains all of the heavier material and a relatively small proportion of pure coal from which it is to be separated; and also to provide novel means whereby the 50 mixture of material being treated may be separated into three different portions.

I shall not undertake at this point to indicate further objects and advantages incident to my invention, but such other objects and advantages will be referred to in the 60 detailed description of the said invention which follows or will be apparent from such description.

In order that the invention may be readily understood and its practical advantages fully 65 appreciated, reference may be had to the accompanying drawings in which I have illustrated one form of mechanical embodiment of the invention.

It is to be understood, however, that the 70 invention is susceptible of embodiment in other forms of construction than that shown and that changes in the details of construction may be made within the scope of the 75 claims without departing from the invention.

In the drawings:

Fig. 1 is a view in vertical longitudinal section of a coal jig apparatus embodying my invention;

Fig. 2 is a top plan view of the same;

Fig. 3 is a transverse vertical sectional view taken on the line 3—3 of Fig. 1;

Fig. 4 is a top plan view of the vibratory jig pan of the apparatus;

Fig. 5 is a view in side elevation of the jig 85 pan structure, with a portion broken away to show a part thereof in section;

Fig. 6 is a view in transverse section of the jig pan structure;

Fig. 7 is a rear end elevation of the jig 90 pan; and

Fig. 8 is a sectional view of the bottom of the jig pan taken on the line 8—8 of Fig. 4.

Referring to the drawings:

1 designates a tank adapted to contain 95 water employed in the washing and cleansing of the coal, which tank is supported by a frame structure 2 in known manner. A portion of the front wall and the rear wall converge as indicated in Fig. 1 to an opening 3 which is adapted to be opened and closed by a valve 4 which may be operated by a lever 5.

The jig pan structure designated as a whole at 10 is suspended upon vertical bars 11 and 11^a from eccentric straps 12 mounted upon eccentrics 13 which in turn are supported upon a revolute shaft 14, upon one end of which fast and loose wheels 15 are provided for the purpose of controlling the operation of the said shaft.

The vertical bars 11 and 11^a are secured by riveting to the opposite sides 16 and 17 of

the jig pan. The lower end of the bar 11 extends through an opening in the horizontal portion or flange of a bracket 18 adjustably secured to the adjacent side wall of the tank 5 1 by means of bolts 19. The upper ends of the bars 11 and 11^a project into holes in the lower ends of projecting portions of the eccentric straps 12 and are secured therein by means of bolts 20. The upper ends of the 10 said bars 11 and 11^a are provided with a plurality of holes or openings therethrough, so that either of the said bars may be adjusted vertically, so as to vary the length thereof, and thereby vary the lateral or transverse 15 pitch or inclination of the bottom 21 of the jig pan. The pitch or inclination of the bottom 21 of the jig pan in a longitudinal direction may be varied by adjusting the bracket 18 in one direction or the other.

20 The bottom of the jig pan is provided with perforations as is usual in such structures.

For the purpose of effecting separation of the pure coal from the relatively heavy material of the character already indicated the 25 jig pan is provided with a series of longitudinally extending plates or bars 25 and with a series of transversely extending plates or bars 26 which radiate from a common distant center. The longitudinally extending bars 30 or plates 25 are mounted directly upon the bottom 21 of the jig pan and are spaced from each other, as shown, so as to provide a series 35 of troughs or runways. The bars 25 are relatively narrow, being approximately one and one-half inches (1½") in width, while the bars 26 are approximately three inches (3") in width. The latter bars are located above the bars 25 and are provided with notches 27, as shown, which notches are of rightangle 40 triangular shape. The bars 25 project into the notches and fit against the vertical walls or shoulders thereof, as best shown in Fig. 6 of the drawings.

As already described, the jig pan is supported so that its bottom has both a longitudinal and a transverse pitch or inclination, in consequence of which the upper left hand corner of said bottom (referring to Fig. 4 of the drawings) is the highest point of the 50 same. The feed chute 30 is located in this corner of the jig pan, so that the mixture to be treated is delivered to the highest point or portion of the bottom thereof. The opposite ends of the three plates or bars 26 located nearest to the feed chute 30 are connected to the side 16 and the left hand end wall of the jig pan. Assuming that the longitudinal and transverse inclinations of the bottom of the jig pan, previously referred to, 55 are equal, and that the opposite ends of the plates or bars 26 are located at points substantially equidistant from the upper left hand corner of the bottom of the jig pan it will be apparent that the opposite ends of each plate or bar are located substantially the

same vertical distance from any assumed lower horizontal plane, so that the top edge of each of the said plates or bars occupies a horizontal plane. It will be apparent, however, that the upper edges of these plates or bars will occupy different levels. By reason of this arrangement in which the first three of the plates or bars 26 referred to occupy substantially horizontal planes it will be apparent that the mixture delivered from the feed chute 30 is evenly distributed over the portion of the bottom of the jig pan included between the third plate 26 and the feed chute. 75

Upon reference to Fig. 4 it will be noted that if the plates or bars 26 were extended upwardly they would ultimately meet at a point upon an extension of the plate or bar constituting the right hand end of the jig pan shown in plan in said figure. As a result of

that arrangement it will be apparent that the relation of the bars 26 to the length of the jig pan or to the bars 25 varies as they approach the right hand end of the jig pan. It will be noted that the bars 26 near the right hand end of the jig pan extend downwardly very nearly at right angles to the bars 25 or almost vertically, whereas the bars 26 at the opposite end of the jig pan extend diagonally across the said jig pan with the consequence that the bar 30 and the first two bars 26 operate to effect equal distribution of the material to be washed upon the jig pan thereafter as the material approaches the opposite end of the jig pan the bars 26 tend to cause downward movement of the cleaned or washed portion of the material to effect discharge of the same over the edge of the side 17.

The mixture of coal, "middlings" or low grade coal, and earthly material, such as stone, slate, etc., is delivered to the jig pan through the feed chute 30, which in the construction shown is triangular in cross section.

Any suitable means may be employed for controlling the rate of feed of the mixture from the feed chute into the jig pan. The material from the chute is delivered into the jig pan in front of or above the first of the transversely extending bars or plates 26. As already stated, the upper edge of each of the first three of these bars or plates occupies a substantially horizontal plane, the said planes occupying different levels. As a result of this arrangement the mixture being treated is spread uniformly over the first or initial part of the jig pan bottom. 115

The end and side walls of the jig pan are extended below the bottom 21 thereof, as shown at 35, and the lower edges of said walls are beveled outwardly as indicated at 36. Extending downwardly from the bottom 21 are a series of plates 37 which are in the same vertical planes as the longitudinally extending bars or plates 25 and constitute distributor baffles. 125

In the operation of the apparatus the jig

pan, by reason of being supported upon the eccentricities 13, will be caused to vibrate in known manner. When the jig pan is vibrated the water in the tank flows upwardly 5 through the perforations in the bottom 21 thereof as it descends. The upward flow occurs, therefore, at intervals. The depending walls 35, the inner bottom edges of which are beveled outwardly, as indicated at 36, 10 operate upon a downward movement of the jig pan to confine the water in the tank within the space surrounded by said walls and tend to cause the same to flow upwardly through the perforations in the bottom 21 of the jig 15 pan as the latter moves downwardly. In other words, these walls prevent the lateral spreading of the water which is located directly underneath the bottom of the jig pan when the latter is moved downwardly. The 20 presence of the spaced plates 37 underneath the bottom 21 of the jig pan operates to render the pulsations of the water through the portions of the jig pan between adjacent bars or plates 25 independent of each other. In 25 other words, the material in one of said troughs, in effect, is treated independently of that in the other troughs.

It will be noted that the end walls and the side wall 16 of the jig pan extend a considerable distance above the bottom 21 thereof, while the portion of the wall 17 of the said pan above the bottom 21 is of a height substantially the same as that of the bar or plate 25 adjacent thereto. As a result of this arrangement, it will be seen that the water which flows upwardly through the perforations in the bottom 21 is caused to flow laterally or transversely of the bars or plates 25 in the direction of the length of the transverse bars or plates 26, and also in the direction of the transverse inclination or pitch of the bottom 21. It may be noted that in practice the depending portions of the side and end walls of the jig pan are referred to as a four-wall baffle, while the upwardly projecting portions of the end walls and the side wall 16 are referred to as a three-wall baffle. In actual practice it has been found that apparently there is no reflex action of the 40 water upon an upward movement of the jig pan, the reason being that the water flows in the direction of least resistance which, in the construction shown, is transversely of the bars or plates 25 and in the direction of the length of the bars or plates 26 which is the direction along which the pure coal flows.

It has been found in practice that the heaviest portions of the refuse material, such as rock, stone, slate, pebbles, sand, pyrite, etc., 45 are caught by the first two or three of the longitudinal bars or plates 25, while the "middlings" material which has some fuel value is caught by the remaining lower plates 25. The material in the jig pan being treated has 50 free movement so that the respective parti-

cles thereof may position themselves in accordance with their specific gravities, in consequence of which the heavier particles, such as the earthy material, etc., previously referred to, settle down upon the bottom of the 70 jig pan almost immediately after the material is delivered from the feed chute, so that that portion of the material being treated is conveyed longitudinally of the jig pan within the first two or three troughs formed by the 75 longitudinal bars or plates 25.

The pure coal being free to move and being lighter than the earthy material and the "middlings" portion of the mixture moves or flows laterally so that due to the inclination 80 of the bottom of the jig pan and to the transverse flow of the water produced by the three-wall baffle a large proportion thereof is discharged from between the third and fourth and fourth and fifth of the transversely extending bars or plates 26. It will be understood that during the operation of the device 85 the coal being the lighter portion of the mixture assumes a position above the heavier portion of the material and is discharged laterally from the jig pan over the upper edge of the side wall 17. As a result of the discharge 90 of the greater proportion of the pure coal from between the third and fourth and fourth and fifth of the transversely extending bars or plates a mixture including a relatively small proportion of pure coal is left for treatment in the main jiggling portion of the jiggling structure.

As the treatment continues the coal which is the lighter is caused to move laterally toward the side wall 17 by the transverse bars or plates 26 and is ultimately discharged over the upper edge of said side wall, while the heavier material is conducted longitudinally by reason of the presence of the longitudinally extending bars or plates 25. In moving longitudinally the heavy material passes through the notches 27. As already indicated, the earthy matter, such as stone, slate, etc. is caught by the first two or three of the bars or plates 25, while the "middlings" portion of the mixture which has some fuel value is caught by the remaining of said bars or plates. Both of these portions are discharged 105 from the lower or right-hand end of the jig pan.

For the purpose of separating the earthy material such as stone, slate, sand, etc., from the "middlings" which contain sufficient coal to be of some fuel value, I have provided an adjustable separating or switch plate 40 which is secured at its outer or rear end to a pivoted or rotatable vertical shaft 41 which is provided with a handle 42 by means of which it may be rotated. The rear or pivoted end portion of the separating plate 40 is located about the middle of the width of a discharge chute 42a. In Fig. 2 of the drawings the separating or switch plate 40 is shown in a 115 120 125 130

middle position in consequence of which the material discharged from the three upper troughs formed by the longitudinal bars or plates 25 is discharged separately from that of the material which is discharged from the three lowermost troughs into which the jig is divided by the bars or plates 25.

Endless conveyer elevators 43 and 44 are provided for removing the material which is discharged from the troughs formed by the bars or plates 25. It will be understood that by adjusting the plate 40 to different positions, as indicated by dotted lines in Fig. 2, the material to be directed to the one conveyer or to the other may be regulated and controlled. If it is desired that an increased quantity or proportion of the material shall be directed to the conveyer 43 the separating plate should be adjusted in a direction as indicated by dotted lines at 45 in Fig. 2. If, on the other hand, it is desired that a greater proportion of the material shall be directed to the elevator or conveyer 44 the separating plate 40 should be adjusted to or toward the position shown by dotted lines at 46. The position which the plate 40 should occupy will depend upon conditions which may be found to exist in each particular case. If it is found that substantially all of the earthy matter is being caught within the first two of the troughs formed by the first two longitudinally extending bars or plates 25 then the separating plate 40 should be moved into position such that its inner or forwardly extending end shall occupy a position in adjacent opposing relation to the rear end of the second of the bars or plates 25. If, however, it is found that a large proportion of the material within the fourth trough is of earthy character the separating plate 40 should be or may be adjusted in the opposite direction, so that its swinging end shall occupy a position in adjacent opposed relation to the rear end of the fourth one of the said bars or plates 25.

The coal which is discharged laterally over the upper edge of the side wall 17 is confined within a restricted portion of the tank 1 by means of a longitudinally extending partition wall 50. The coal is removed from the bottom of the compartment formed by the wall 50 and the side and end walls of the tank structure by means of an endless conveyer elevating structure shown at 51. The endless conveyer elevating structures 43, 44 and 51 are of usual construction, being supported at their upper and lower ends upon sprocket wheels. The sprocket wheels at the upper ends of the structures are mounted upon a shaft 53 upon one end of which a spur gear 54 is mounted which is in engagement with a pinion gear 55 upon a shaft 56 which is driven by means of a belt 57, which in turn is driven by means of a driving wheel 58 mounted upon the shaft 14 previously referred to.

It may happen that there is an interruption in the supply of the mixture of coal and impurities to the chute 30, which, of course, will result in an interruption of the supply to the jig pan. If the jig pan continues to operate as it usually does the treatment and separation continues with the result that the bottom of the jig pan becomes bare or clean. This is objectionable, because when the feed is resumed the probabilities are that some coal will travel along the clean bottom of the pan within the longitudinally extending troughs formed by the bars or plates 25 and will be discharged with the impurities, such as stone, slate, etc. and "middlings". It is desirable, therefore, that means be provided which upon the interruption of the feed of the material to be treated will prevent the discharge of material from the rear ends of said troughs.

The means or mechanism for this purpose comprises a plate 60, constituting a gate, movably supported by means of parallel arms 61 at the rear end of the jig structure. The outer swinging ends of these arms have pivotal connection with the plate 60. One of these arms is provided with an extension 62 beyond its pivot to which a connecting rod 63 is connected, the opposite upper end of which is connected to an arm 64 which is rigidly connected with the rear end of a rotatable rod or shaft 65 which is mounted in bearings upon the upper portion of the jig structure adjacent the plane of the side wall 16 thereof. The front end of the said rotatable bar or shaft 65 extends through the chute 30 adjacent one side thereof. A diaphragm 66 is mounted upon the said rod or shaft within the said chute and when no material is flowing through the chute occupies a horizontal position. When the diaphragm is in such position the gate 60 occupies closed position. The diaphragm is illustrated in the position it occupies when coal is flowing through the chute. In such position the said diaphragm occupies a substantially vertical plane, the plate 60 at such time occupying an elevated open position, as shown in Fig. 7 of the drawings. In such position the material is allowed to be discharged from the rear end of the jig pan structure.

It will be understood that it is the weight of the mixture of coal, stone, slate, etc. upon the diaphragm 66 that moves the same into the open position, as shown in the drawing, to move the plate or gate 60 also into open position.

Upon interruption of the flow of the material to be treated through the chute the weight of the plate or gate 60 is sufficient to overcome the weight of the diaphragm 66, connecting rod 63, etc., whereby the said plate or gate is allowed to move into closed position. To facilitate the opening and closing of the gate the rotatable rod or shaft 65 is provided at its front end with a cross bar 70

upon one end or the other of which a weight 71 may be adjustably mounted. The said weight may be mounted upon either end of the bar 70 as may be necessary, depending upon 5 the relative weights of the closing plate or gate and the diaphragm 66 and connecting rod 63, etc.

It may be stated that in the operation of the apparatus a minimum thickness of the 10 bed of material upon the bottom of the jig pan is maintained at all times and that the maximum thickness of the bed of material upon the bottom of the jig pan is equal approximately to the width of the transversely 15 extending bars or plates 26.

It will be seen that by my invention I have provided an apparatus of unitary structure by the employment of which the pure coal may be separated most efficiently from the 20 material, such as stone, slate, etc., and "middlings" which it is desired to eliminate, and also that the greater portion of the pure coal fed into the jig pan is delivered or discharged therefrom as a pure product during the 25 initial part of the operation before it has reached the main jiggling area of the jig pan; that the bed of material upon the bottom of the jig pan is maintained in a state of maximum porosity due to the fact that the particles thereof are free to move and to expand; that the material being treated may be divided into three separate parts which thereafter may be treated and handled as may be desired; that the discharge of the 30 heavier material of the mixture being treated is automatically interrupted upon the interruption of the feed of material to the jig pan; and that the pulsations of the water through the portions of the bottom of the jig 35 pan between the longitudinally extending bars or plates 25 are equalized so as to effect separation of the coal from the portions of the mixture which it is desired to eliminate. Although I have described my invention 40 as embodied in a structure for treating and cleaning coal, it will be understood that it may be adapted and employed for the treatment of other substances which include portions of different specific gravities which it 45 is desired to separate.

Having thus described my invention, what I claim and desire to secure by Letters Patent is:

1. A coal jig comprising a jig pan having 55 a perforated bottom and having longitudinally extending spaced plates secured in adjacent relation to the top side of said bottom, and also having transversely extending spaced plates secured in spaced relation to each other adjacent the top side of said bottom, the latter plates converging toward a central point located outside of and above one end portion of the jig pan, the said latter plates being situated above the first-named plates.

2. A coal jig comprising a jig pan having a perforated bottom and having longitudinally extending narrow plates secured in spaced relation to each other adjacent the top side of the said bottom and also having 70 transversely extending plates radiating from a common center and secured in spaced relation to each other above the top side of the said bottom, the said latter plates being of greater width than the former and being 75 provided with notches into which the upper edge portions of the first-named plates extend, the said notches forming passageways transversely of and underneath the said second-named plates. 80

3. A coal jig comprising a jig pan having relatively narrow plates extending longitudinally thereof in spaced relation to each other and in adjacent relation to the top side of the bottom of said pan, and also having 85 transversely extending plates arranged in spaced relation to each other above the first-named plates and in adjacent relation to the bottom of the said jig pan, said transversely extending plates being provided with notches 90 through which the material guided by the said longitudinally extending plates may pass, and means for separating the material which may be discharged from between the first-named plates into two different portions. 95

4. A coal jig comprising a jig pan having a bottom and side and end walls, the said bottom being exposed and the said walls extending a distance below the said bottom, and one of the side walls, and the end walls 100 extending a relatively great distance above said bottom, and the other of said side walls extending a relatively short distance above the said bottom, means for supporting said jig pan with its bottom inclined longitudinally and laterally from the first-named side wall, and the said jig pan having longitudinally extending bars spaced from each other and mounted in adjacent relation to the top side of the said bottom, and also having baffle plates located underneath the said bottom and in the vertical planes of the said bars, and spaced plates extending transversely of the said bars and supported in spaced relation to each other adjacent the top side 105 of the bottom of said pan, said transversely extending plates being of greater width than the said bars and being provided with notches into which the said bars extend, which notches provide passageways through which the impurities which may be intermingled with the coal are adapted to pass. 115

5. A coal jig comprising, in combination, a jig pan inclined both longitudinally and transversely, a feed chute for delivering a 120 mixture of coal and impurities to one corner of the said jig pan, the end walls and the side wall adjacent the said chute extending a relatively great distance above the bottom of said jig pan while the other side wall of 125

said jig pan extends but a short distance above the bottom of said jig pan, bars or plates secured in spaced relation to each other adjacent the top side of the bottom of 5 said jig pan, said bars extending longitudinally of the said pan, plates secured in spaced relation to each other and extending transversely of said jig pan and being secured so the bottom edges thereof occupy positions 10 adjacent the top side of the bottom of said jig pan, said transversely extending plates being provided with notches into which the said longitudinally extending bars or plates project, the first three of the said transversely 15 extending bars located nearest to the said feed chute having their upper edges located in substantially horizontal planes, while the upper edges of the remaining transversely extending plates are inclined with respect to 20 a horizontal plane, substantially as described.

6. A coal jig comprising in combination a jig pan, means for supporting said jig pan with its bottom inclined both longitudinally and transversely, whereby one edge and one 25 end of said bottom are higher than the opposite edge and end respectively, a feed chute for feeding a mixture of coal and impurities to said jig pan, the delivery end portion of said feed chute being located in the highest 30 corner of the said jig pan, means for providing troughs extending longitudinally of the said jig pan, transversely extending plates supported in spaced relation to each other with the bottom edges thereof adjacent 35 the top side of the said bottom, the top edges of said plates extending a short distance above the top edges of the opposite sides of the said troughs, and the said transversely extending plates being provided with notches 40 in their lower edges through which material may pass as it moves through the said troughs toward the discharge end of the said jig pan, the opposite ends of each of a number of said transversely extending plates 45 near the feed chute occupying positions sub-

stantially equi-distant from said corner whereby the upper edges thereof occupy substantially horizontal planes, substantially as described.

7. A coal jig comprising a jig pan having a bottom which is inclined both longitudinally and transversely, means for delivering material to be treated to substantially the highest point of the said bottom, bars extending in spaced relation to each other both longitudinally and transversely of the said bottom upon the top side thereof, the transversely extending bars having passageways therethrough upon the undersides thereof, and means for causing water to flow transversely of the length of the said bottom and substantially in the direction of the length of the said transverse bars, substantially as described.

8. In coal washing apparatus comprising a tank containing water, the combination of a jig pan located in the said water the said jig pan having a bottom provided with perforations and also having spaced narrow bars secured therein in adjoining relation to the top side of the said bottom and extending longitudinally thereof and also having plates secured within the said jig pan in adjoining relation to the top side of the said bottom, which plates extend diagonally of the length of the said jig pan and being provided with notches located within the spaces between the said bars and forming passageways, means for effecting vibration of the said jig pan, and plates mounted upon the under side of the bottom of the jig pan in vertical planes for directing independent streams of water upwardly through the perforations in the bottom of the said jig pan between the said bars which streams are caused by the vibration of the said jig pan.

In testimony that I claim the foregoing as my invention, I have hereunto signed my name this 11th day of May, A. D., 1925.

MAXIMILIAN S. HACHITA.
